ATTACHMENT FOR SCALES

Filed Sept. 22, 1927

UNITED STATES PATENT OFFICE

FRED B. HAMBLIN AND GEORGE B. HAMBLIN, OF CLEVELAND, OHIO

ATTACHMENT FOR SCALES

Application filed September 22, 1927. Serial No. 221,234.

This invention relates to attachments for scales, and consists in the novel construction hereinafter disclosed.

An object of the invention is to provide an attachment for beam scales, whereby the weighing operation is expedited, and which will directly indicate the correct balance or exact weight, or over and underweight.

Another object of the invention is to provide an indicating mechanism which may be connected with the beam of a beam scale, whereby a direct reading of the beam balance may be taken, when load is placed on the scale.

Additional advantages of the invention will be apparent from the following detailed description thereof, taken in connection with the accompanying drawing in which

Fig. 1 is a front elevation, partially in section, of the mechanism.

Fig. 2 is a vertical sectional view through the mechanism.

In the embodiment illustrated in the drawing the mechanism is shown connected to a beam 1 of a beam scale. The connection includes an arm 2 in the form of a rod that is attached to the end of the beam and extends outwardly therefrom. The arm 2 carries at its outer end a U-shaped bracket 3. The arm 2 extends through a slot 4 in a housing 5 so that its inner end carrying the bracket 3 is within the housing. The housing 5 forms a casing for the indicating mechanism and is mounted on adjustable legs 6 so that it may be positioned on a support adjacent to the beam scale and leveled up to cooperate with said scale. For this purpose the legs 6 are preferably made adjustable.

The housing is substantially in the form shown in the drawing and includes a lower section which develops into a fan-shaped top section 7 that carries segmental sight windows 8 on its front and rear walls at the top of said section 7. A double face indicating chart 9 preferably having the zero indication at the center and numbered graduations extending on either side of the chart, as clearly shown in Fig. 1 of the drawing, is positioned within the upper part of the housing and is readable through each of the windows

8. Within the lower part of the housing 5 there is a U-shaped bracket 10, the base of said bracket being supported by the bottom wall of the housing and the arms of said bracket extending upwardly in said housing 55 and terminating in bearing supports 11. Within the bearing supports 11 are set ball bearing members 12 in which a transverse shaft 13 is journaled at each end. The shaft 13 is enlarged at its central portion to form 60 a drum 14. The extremity of the upper arm of the bracket 3 supports an adjustable screw rod 15, said rod 15 carrying an equalizing lever 16 at its lower end with which it has pivot connection. Attached to each end of the 65 equalizing lever is an adjustable eye 17 into each of which is fitted the end of a cord 18, said cords 18 extending around a portion of the circumference of the drum 14 and being attached thereto by set screws 19, or in any 70 other suitable manner. The lower extremity of the bracket 3 carries an adjustable screw rod 20, which, in turn, carries an equalizing lever 21. Each extremity of the lever 21 carries an adjustable screw eye 22, into each of 75 which is connected a cord 23, said cords 23 extending partially around the circumference of the drum 14 in a direction opposite to the cords 18, said cords 23 being connected with the periphery of said drum by set screws 24, 80 or in any other suitable manner. By reference to Fig. 2 of the drawing it will be noted that the arrangement of the cords 18 and 23 is such that the cords 18 extend around the drum in one direction at a position on the 85 drum outside of the cords 23, which extend in the opposite direction, this positioning of the cords being provided for by the difference in length of the levers 16 and 21. It will also be noted that, by the provision of the 90 screw eyes 17 and 22, the pull on each of the cords 18 and 23 may be adjusted. While cords have been illustrated in the drawing, it is obvious that tape, springs or other connecting devices between the bracket 3 and the 95 drum 14 may be substituted, if desired.

A pointer arm 25 is carried by the drum 14 near its inner end. The arm 25 extends upwardly and its extremity is formed as a pointer coordinating with one of the charts 100

9. The said arm carries a branch extension 26, said extension being formed of a rod that extends backwardly from the arm 25 and then upwardly to constitute a pointer on the 5 rear face of the indicating chart. The lower end of the indicating arm 25 carries a counterweight 27, which is adjustable for centering purposes by providing settable weight devices 28 adjustable in slots on either side of 10 the center of gravity of said counterweight.

In order to provide for smoothness of operation of the indicating mechanism the mechanism is equipped with a dash-pot construction which includes a dash-pot cylinder 29 supported in the bottom of the housing and in which there is a piston 30, said piston being provided with an adjustable dash 31. The piston carries a piston rod 32 that extends upwardly through a packed opening in the 15 cover 33 of the cylinder. The lower extremity of the bracket 3 has a downwardly extending lug 34 which is connected with the upper end of the piston rod 32 by a pivoted link 35. It will be understood that the piston 30 20 operates in oil and that the adjustable dash 31 provides means for the adjustment of the flow of oil so that the speed of operation of the device may be controlled.

It is now clear that the bracket 3 is a floating bracket and is not mounted on any pivots or other supports than the scale beam 1 which operates said bracket, a dash-pot device which controls the speed of operation of the bracket, and the flexible connections 18 and 23 connecting the bracket with the drum 14. Accordingly, the entire bracket 3 is always moved in the same direction in which the scale beam moves.

From the foregoing description it will be 40 understood that, as the beam 1 oscillates responsive to load, the weight indication is accomplished by the counterweighted pointer device, which moves responsive to the extent of oscillation of the beam as against the 45 counter load of the pull on the cords 18 and 23 carried by the bracket 3. It is obvious that the disclosed mechanism may be readily applied to any type of beam scale and that it affords a direct means of indicating the 50 balancing point of the scale. As the chart is graduated in both directions from the center, it provides for indicating over and underweight. It also provides means of determining the sensitiveness of the scale. It is clear, 55 therefore, that it accomplishes adequately the purposes of the invention.

We are aware that the invention may be modified in various particulars without departure from the spirit and scope thereof.

Therefore, we do not limit ourselves to un- 60 essential details of construction, but what we claim and desire to secure by Letters Patent is: —

1. An attachment for scales comprising a 65 housing, means for adjusting the elevation

of said housing, a rockable shaft supported within the housing, a drum carried by said shaft, a counterweighted indicating arm pivoted coaxially with the shaft, an oscillating member adapted to be connected to the beam of the scale and to oscillate therewith, and flexible connections between said member and the drum whereby the indicating device responds in movement to the movement of the beam of the scale. 70

2. An attachment for scales comprising a housing, a rockable shaft having ball bearing supports supported within the housing, a drum carried by said shaft, a counterweighted indicating arm pivoted coaxially with the shaft, an oscillating member adapted to be connected to the beam of the scale and to oscillate therewith, and flexible connections between said member and the drum whereby the indicating device responds in movement 75 to the movement of the beam of the scale. 80

3. An attachment for scales comprising a housing, a rockable shaft having ball bearing supports supported within the housing, a drum carried by said shaft, a counterweighted indicating arm pivoted coaxially with the shaft, an oscillating member adapted to be connected to the beam of the scale 85 and to oscillate therewith, flexible connections between said member and the drum whereby the indicating device responds in movement 90 to the movement of the beam of the scale. 95

4. A device of the character described comprising a pivot element mounted for rocking movements, an indicating arm attached to said pivot element for operation thereby, an indicating chart coordinated with said arm, a bracket, a plurality of flexible connections between said bracket and said pivot element for rocking said pivot element in opposite directions by vertical movements of 100 said bracket, and means for connecting said bracket to the beam of a beam scale for operation thereby and always in the same direction in which the scale beam operates. 110

5. An attachment for scales comprising a casing having a slot in one side thereof, a pivot element mounted in said casing for rocking movements, an indicating arm attached to said pivot element in said casing for operation by said pivot element, an indicating chart coordinated with said indicating arm, a bracket in said casing, a plurality of flexible connections between said bracket and said pivot element for rocking said pivot element in opposite directions by vertical movements of 115 said bracket from and to a starting position, and an arm in connection with said bracket and projecting through said slot in said casing for connection with the beam of a beam scale to be operated thereby. 125

6. An attachment for scales comprising a 130

casing having a slot in one side thereof, a pivot element mounted in said casing for rocking movements, an indicating arm attached to said pivot element in said casing
5 for operation by said indicating arm, a bracket in said casing, a plurality of flexible connections between said bracket and said pivot element for rocking said pivot element in opposite directions by vertical movements
10 of said bracket from and to a starting position, an arm in connection with said bracket and projecting through said slot in said casing for connection with the beam of a beam scale to be operated thereby, and means in
15 connection with said bracket for controlling the speed of operation of said bracket by said actuating arm when said actuating arm is moved by the beam of a beam scale as aforesaid.
